CHAIR

Hugo Melder, Mahr.-Ostrau-Witkowitz,
CzechoslovakiaApplication June 28, 1929, Serial No. 374,433
In Germany November 6, 1928

1 Claim. (Cl. 155—50)

This invention relates to a chair made from tubing of any kind, especially steel tubing, or from solid material, such as wood and the like and adapted particularly for use in motor cars, omnibuses, railroad cars, etc.

5 Chairs in which the seat and back form a unit resting on a separate support are known already, but they suffer from the drawback that they are not elastic. In other known types of chairs the back and seat are bent from a piece of tubing in 10 one operation, which has the effect that shocks are transmitted from the back to the seat and vice versa.

The invention eliminates these drawbacks by 15 providing a chair, the seat of which is not in contact with the back, so that both the seat and the back can swing freely and independently of one another. Furthermore, the chair is designed so as to render its production simple and cheap. To 20 attain the objects of the invention the chair is formed by a base including two spaced horizontal tubular members which are uniformly bent upwardly in the rear so as to form a closed and freely swinging frame for the back while the front portions of the base members are also bent up and 25 thence extended in horizontal direction to form a support for the seat.

By way of example, the invention is illustrated in the accompanying drawing, in which a chair 30 is shown in perspective.

Referring to the drawing, the chair consists of a unitary tube made for instance of a special steel. The base comprises two spaced horizontal

tubular members 17, 17' which are bent up in front to form vertical supports 1, 1' which then extend laterally to form the side supports 9, 9' preferably connected at their ends by the member 10 and carrying the seat 3. The rear portions of the members 17, 17' are bent up also and 60 form the side supports 4, 4' connected on top by the member 8 and carrying the covering 6 for the back. As indicated in the drawing, the side supports 9, 9' are united by the connecting part 10 and project between the upwardly extending portions 4, 4' at a distance from the latter to be out 65 of contact with them. In this way the seat as well as the back can freely oscillate independently of one another, since they are not connected. On the other hand, shocks and vibrations affecting 70 the back and seat are directly transmitted by them to the base members 17, 17' where they are stopped without having an opportunity of being propagated from one part to the other.

I claim:—

A chair comprising a unitary metal tube bent to form a rectangular frame, one end of said frame being bent up vertically to form the rear supports and the back, the opposite end of said frame being bent up vertically to a predetermined degree to form front supports and then bent horizontally towards the back to form the seat, the central portion of said frame connecting said front and rear supports while retaining its original 80 position and thus forming a base for the chair. 85
